UNITED STATES PATENT OFFICE.

SIMEON S. JACKSON, OF BOSTON, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

FILLING-FEELER MECHANISM FOR LOOMS.

Application filed November 4, 1920. Serial No. 421,635.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Filling-Feeler Mechanisms for Looms, of which the following is a specification, reference being had therein to the accompanying drawings.

10 The invention has relation to the so-called filling-feeler mechanisms which are employed in looms for the purpose of detecting when the supply of weft or filling contained in a loom-shuttle has become depleted 15 to the predetermined extent, and thereupon bringing about action, usually automatic weft replenishment, to forestall delivery of the last end of the said supply from the shuttle into the cloth being woven, in order 20 to avoid the introduction of a short pick of weft or filling into the cloth and consequent injury to the value of the latter.

25 A filling-feeler mechanism comprises, ordinarily, a weft or filling-feeler, devices which under the governance of the filling-feeler serve more immediately to bring about the action aforesaid, or call the change as it sometimes is expressed, and a so-called controller located intermediate the filling-feeler and the said devices, itself governed 30 by the filling-feeler, and in turn controlling such devices. In some cases a train of connecting devices takes the place of a controller.

35 The general object of the invention is to do away with the various types, forms, and constructions of controllers and other intermediate devices which heretofore have been used or proposed for operatively combining and connecting together a feeler-device and a vertically-movable latch or dog forming a part of the devices for calling a change, and to provide in the place thereof much simpler means for the purpose of controlling the said latch or dog and its engagement by the weft-hammer, or other actuator, for the purpose of actuating the said devices to call the change.

40 In accordance with the invention, I connect and combine an arm or other part that moves laterally when the filling-feeler detects substantial depletion, with a vertically-movable latch or dog such as aforesaid, by means of a flexible connector extending trans-

versely from said arm (or other laterally-movable part) to and around a guide by which its direction is changed so that it extends thence in a vertical direction to the latch or dog, whereby it serves to determine the position up or down of the latch 60 or dog and its engagement by the weft-hammer or other actuator.

An important application of the invention is in connection with filling-feeler mechanisms of the class provided with side-slipping feeler-devices, although the invention is not necessarily restricted to employment in that precise connection. Side-slipping feeler-devices are in general characterized by having a laterally-movable feeler-member which by engagement of the shuttle-contained supply of weft or filling therewith at the time of each successive feeling action is held from lateral movement, that is to say is held from movement longitudinally of the weft or filling-carrier occupying the shuttle, until the remaining portion of the said supply is too small to prevent such movement. At such stage in the depletion of the supply the feeler-member is 80 displaced laterally in a feeling action, and as a result of such displacement the change is called. This class comprises two types of the devices, to either of which the present invention is applicable. These two types 85 are, first, the type in which the tendency of the feeler-member to move laterally results from forwardly-directed contact-pressure acting against a laterally offset feeling end or tip; and second, the type in which the 90 tendency of the feeler-member to move laterally is due to the application of the yielding force of a spring or other convenient means at the time of the feeling action.

The drawings show an illustrative embodiment of the invention in a form of feeler-mechanism having a side-slipping feeler-device of the type first mentioned. The application of the features of the invention in connection with feeler-devices of the second-type referred to, and in connection with other kinds of feeler-devices, will be obvious to those skilled in the art.

In the drawings,—

Fig. 1 is a top view of certain parts at 105 one side of a loom, including the said illustrative embodiments of the invention, the parts being shown in their normal positions.

Fig. 2 is a front view of the parts at the right hand side of Fig. 1.

Fig. 3 is a view looking from the left in Fig. 2, the breast-beam being in section 5 in a vertical plane, and the support of bracket *b* being broken away.

Having reference to the drawings,—

Small portions of the breast-beam 1 and lay-beam 2 of a loom are shown, 3 being 10 the front-plate of the shuttle-box upon the end of the lay-beam which is adjacent the feeler-mechanism, and 4 a shuttle occupying the said shuttle-box. The usual openings 3^a, 4^a, in the plate and the front-wall of the 15 shuttle permit entrance of the contact-portion or tip 11 of the feeler-device as the lay beats up, to provide for contact between the end of the said contact-portion or tip 11 and the filling-mass 6 upon the filling-carrier 7 20 occupying the shuttle.

The feeler-device shown in the drawings is one of convenient construction, it comprising as heretofore in some cases a carrier-member 8 that is movable forwardly and 25 rearwardly in the loom, and a feeler-member 9 carried by said carrier-member.

The carrier-member 8 is, as more or less common, a slide working in a guideway at 12^a upon a small stand 12 attached to the 30 outer end of a main supporting stand 13 extending outward from the breast-beam. A cap or cover-plate 12^c bridging the guideway and holding the slide down therein, is secured in place by screws 12^a, 12^b. The 35 forwardly extending reduced extension 8^a of the slide, working in a hole through an upstanding portion 12^b of the forward part of stand 12, is as usual surrounded between the body of the slide and the upstanding 40 portion 12^b of stand 12 by an expanding spiral spring 8^b which operates to keep the carrier-member 8 normally in its rearward position, and to return it to that position after having been pushed forward in a 45 feeling action by the pressure of the shuttle-contents against the end 11^a of the feeler-member.

The feeler-member 9 is, in this instance, mounted upon a pivotal stud 10 on the carrier-member 8, with capacity for transverse movement in a horizontal plane, and has a rearwardly projecting contact-portion or tip 11, the filling-engaging end 11^a of which is offset laterally with relation to the pivot 55 of the feeler-member. To this lateral offsetting is due the tendency of the feeler-member to swing around its pivot under the forwardly acting pressure of the shuttle-contents against its contact-portion in a 60 feeling action.

The means of holding the feeler-member normally in its presentation position shown in Fig. 1, with its forwardly-projecting arm 9^a in contact with a stop 8^f upon 65 carrier 8, is in this instance a contracting

spiral spring 11^b having one end thereof engaged with an arm 9^b of the feeler-member at the side of pivot 10 opposite that at which filling engaging end 11^a is located, and its opposite end engaged with a stud 70 or pin 8^e projecting from slide 8. When the feeler-member in a feeling action swings around pivot 10 as its contact-portion or tip 11^a slips laterally along a practically empty filling-carrier 7 in a feeling action, 75 the arm 9^b is swung laterally away from the said stop 8^f.

The devices which serve more immediately to call the change, when lateral movement of the feeler-member occurs in a feeling action are in this instance the well-known combination comprising a latch or dog 18, an upstanding arm 19 with which the latch or dog is connected, and a controlling rockshaft 20 upon which said arm 85 is fixed. The said controlling rockshaft in practice is connected operatively with the replenishing instrumentalities (not shown) of the loom, or it might be with loom-stopping mechanism, so that when the rockshaft 90 is rocked either replenishment or loom-stoppage, as the case may be, will be brought about. The latch or dog is connected by means of a pivot 18^b with the arm 19, with capacity to swing up and down in a vertical plane, and extends rearward from the arm, it having a lateral projection or tooth 18^a for cooperation with the actuator; herein as usual the weft-hammer or gooseneck 21, and the latter having a shoulder 21^a to 100 cooperate with said lateral projection or tooth. As usual, when the latch or dog occupies a position in which its tooth is clear of the path in which shoulder 21^a moves as the weft-hammer or gooseneck 21 105 swings forward and rearward, the weft-hammer moves forward without engaging with the latch or dog, but when the latch or dog changes its position so as to carry its tooth into the path of the shoulder, the latter engages the tooth and the weft-hammer or gooseneck actuates the latch or dog, etc., to call the change.

The flexible connector *a*, by means of which in accordance with the invention the 115 feeler-member and latch or dog are operatively combined and connected together, is a wire or cord that in this instance is connected with the arm 9^a of the feeler-member, and extends therefrom transversely toward the latch or dog 18. The direction-changing guide *b*, around which the connector changes its direction and continues vertically to the latch or dog, is in the case of the illustrated construction a pulley or 120 sheave located adjacent the latch or dog, and journaled upon a small bracket *b'* that is attached to the inner end of supporting stand 13 by means of a screw or bolt *b*². A slot *b*³ in the bracket provides for adjust- 125

ment of the guide forward or rearward into proper working relations with the associated parts.

The relations of the latch or dog with respect to the actuator therefor, and the manner in which the connector is utilized to control the latch or dog, may vary in practice. In the case of the illustrated construction the latch or dog is intended to occupy normally a relatively elevated position with its tooth 18^a above and clear of the path of the shoulder 21^a of the weft-hammer or goose-neck, and for the purpose of calling a change, is intended to descend to place the said tooth in the said path so that the engagement of the moving shoulder with the tooth shall cause the latch or dog, arm 19, and controlling rock-shaft 20 to be moved. Accordingly, the connector *a* is arranged so that it passes over guide *b* and a portion thereof depending from the guide is engaged with a pin *c* upon an extension *c'* projecting down from the latch or dog. The connector is of such a length that when the feeler-member occupies its presentation position shown in Fig. 1, with its arm 9^a in contact with stop 8^f on the carrier 8, the latch or dog is supported in the relatively elevated position aforesaid. The tension of the spring 11^b connected with the feeler-member is sufficiently strong to keep the latch or dog elevated and cause such contact to occur, so long as the feeler-member is not forcibly displaced.

The distance from the arm 9^a to the guide *b* is so great, and the amplitude of the forward and rearward movements of the feeler-device that take place in the feeling actions is so short, that the portion of the connector that is engaged with arm 9^a swings forward and rearward in unison with the feeler-device without occasioning any or noticeable movement of the latch or dog vertically.

In operation, when the feeler-member moves laterally in a feeling action because the supply of weft or filling within the shuttle is substantially depleted and fails to prevent such movement, the inward swinging movement of arm 9^a of the feeler-member permits connector *a* to draw inward and around the guide *b* and allows the latch or dog 18 to lower so as to place its tooth in the path of the shoulder of the weft-hammer, and the engagement of said shoulder with said tooth thereupon takes place, with the result that a change is called.

Provision is made by means of screw *a'*, connecting the connector with the arm 9^a of the feeler-member, for adjustment of the latch or dog vertically when necessary in order to cause it to be held at the proper height above the path of the shoulder 21^a of the weft-hammer or gooseneck, or to provide for proper engagement of the tooth 18^a with the shoulder 21^a. The connector is adjustable longitudinally by means of the said screw and nuts upon its threaded stem at opposite sides of the swivel-piece *a'*, shown in Fig. 1, carried by arm 9^a of the feeler-member. Further provision for this adjustment is provided for by means of a slot *c*² in the upper portion of extension *c'* of latch or dog 18, and a clamping screw *c*³ occupying the said slot. The said extension is a small bar that is fastened to the latch or dog 18 at one side of the latter by means of the clamping screw *c*³, and the slot *c*² provides for adjustment of the said extension or bar vertically with reference to the latch or dog. According as the pin *c* is located by means of one or the other of these provisions for adjustment higher or lower with reference to the latch or dog, the latch or dog will be supported by the vertically extending portion of the connector *a* in a higher or lower relation with respect to the shoulder 21^a of the weft-hammer.

What is claimed as the invention is,—

1. In filling-feeder mechanism for looms, the combination with an arm or other part that moves laterally when the filling-feeder detects substantial depletion, and a vertically-movable latch or dog constituting an element of the devices for calling a change, of a direction-changing guide adjacent the latch or dog, and a flexible connector extending transversely from said arm or part to and around said guide and thence vertically to the latch or dog, and by its tension determining the position up or down of the latter and its engagement by the weft-hammer or other actuator.
2. In filling-feeder mechanism for looms, the combination with a feeler-member that reciprocates forwardly and rearwardly in the feeling action and moves laterally when the weft or filling is substantially depleted, and a vertically-movable latch or dog constituting an element of the devices for calling a change, of a direction-changing guide adjacent the latch or dog, and a flexible connector extending transversely from the feeler-member to and around said guide and thence vertically to the latch or dog, and by its tension determining the position vertically of the latch or dog and its engagement by the weft-hammer or other actuator.
3. In filling-feeder mechanism for looms, the combination with a feeler-member that reciprocates forwardly and rearwardly in the feeling action and is deflected sidewise by the feeling action when the weft or filling is substantially depleted, a spring which gives said feeler-member its normal position, and a vertically movable latch or dog constituting an element of the devices for calling a change, of a direction-changing guide adjacent the latch or dog, and a flex-

ible connector extending transversely from the feeler-member to and around said guide and thence vertically to the latch or dog and by the tension of which the position up or down of the latter and its engagement by the weft-hammer or other actuator are controlled.

4. In filling-feeler mechanism for looms, the combination with a feeler-device comprising a reciprocating carrier and a feeler-member mounted thereon which moves laterally when the weft or filling is substantially depleted, and a vertically movable latch or dog constituting an element of the devices for calling a change, of a direction-changing guide adjacent the latch or dog, and a flexible connector extending transversely from the feeler-member to and around said guide and thence vertically to the latch or dog, and by the tension of which the position up or down of the latter and its engagement by the weft-hammer or other actuator are controlled.

5. In filling-feeler mechanism for looms, the combination with a feeler-device comprising a reciprocating carrier and a feeler-member mounted thereon which moves laterally when the weft or filling is substantially depleted, a spring which gives said feeler-member its normal position, and a vertically movable latch or dog constituting an element of the devices for calling a change,

of a direction-changing guide adjacent the latch or dog, and a flexible connector extending transversely from the feeler-member to and around said guide and thence vertically to the latch or dog, and by the tension of which the position up or down of the latter and its engagement by the weft-hammer or other actuator are controlled.

6. In filling-feeler mechanism for looms, the combination with a feeler-device comprising a reciprocating carrier and a feeler-member which moves laterally when the weft or filling is substantially depleted, a vertically-movable latch or dog which constitutes an element of the devices for calling a change, and a weft-hammer or other actuator for said latch or dog, of a direction-changing guide adjacent the latch or dog, a flexible connector extending transversely from the feeler-member to and around said guide and thence vertically to the latch or dog, and by its tension controlling the latter, and a spring which gives the feeler-member and latch or dog their positions while a sufficiency of weft or filling is present.

In testimony whereof I affix my signature in presence of two witnesses.

SIMEON S. JACKSON.
